United States Patent

Des. 242,125

Patented Nov. 2, 1976

242,125

BOTTLE

Juan Enrique Barcelo de Torres, Calle Francisco
Silvela 21, Madrid, Spain

Original design application Apr. 17, 1974, Ser. No.
461,715. Divided and this application June 12,
1975, Ser. No. 586,401

Term of patent 14 years

Int. Cl. D9—01

U.S. Cl. D9—68

FIG. 1

FIG. 2

FIG. 4

FIG. 1 is a side elevational view of a bottle showing my new design, the opposite side being a mirror image thereof;

FIG. 2 is a front elevational view, the rear being the same in appearance except for the omission of the circular element just below the neck;

FIG. 3 is a top plan view; and

FIG. 4 is a bottom plan view thereof.

This is a division of design application Ser. No. 461,715, filed Apr. 17, 1974.

I claim:

The ornamental design for a bottle, as shown and described.
